US00D868720S

(12) **United States Design Patent** (10) Patent No.: **US D868,720 S**
(45) Date of Patent: **** Dec. 3, 2019**

(54) **ANTENNA**

- (71) Applicant: **ANTENNAS DIRECT, INC.**,
Ellisville, MO (US)
- (72) Inventors: **Corey Feit**, St. Louis, MO (US); **John Edwin Ross, III**, Moab, UT (US);
Richard E. Schneider, Wildwood, MO (US)
- (**) Term: **15 Years**
- (21) Appl. No.: **29/627,951**
- (22) Filed: **Nov. 30, 2017**

Related U.S. Application Data

- (63) Continuation of application No. 29/580,049, filed on Oct. 5, 2016, now Pat. No. Des. 809,490, which is a continuation-in-part of application No. 14/308,422, filed on Jun. 18, 2014, now abandoned, and a continuation-in-part of application No. 29/430,632, filed on Aug. 28, 2012, now abandoned, which is a continuation-in-part of application No. 29/376,791, filed on Oct. 12, 2010, now Pat. No. Des. 666,178, said application No. 14/308,422 is a continuation-in-part of application No. 13/759,750, filed on Feb. 5, 2013, now Pat. No. 8,994,600, which is a continuation-in-part of application No. 12/606,636, filed on Oct. 27, 2009, now Pat. No. 8,368,607, which is a continuation-in-part of application No. 12/050,133, filed on Mar. 17, 2008, (Continued)

OTHER PUBLICATIONS

Notice of Allowance for U.S. Appl. No. 29/580,049, filed Oct. 5, 2016 which claims priority to the same parent application as the instant application, Nov. 16, 2017, 17 pages.

Primary Examiner — Michael C Stout

Assistant Examiner — Benjamin M Weeks

(74) Attorney, Agent, or Firm — Harness, Dickey & Pierce, P.L.C.; Anthony G. Fussner

(57) **CLAIM**

The ornamental design for an antenna, as shown and described.

DESCRIPTION

FIG. 1 is a perspective view of an antenna, showing our new design;

FIG. 2 is a back perspective view of the antenna shown in FIG. 1;

FIG. 3 is a front view of the antenna shown in FIG. 1;

FIG. 4 is a back view of the antenna shown in FIG. 1;

FIG. 5 is a right side view of the antenna shown in FIG. 1;

FIG. 6 is a left side view of the antenna shown in FIG. 1;

FIG. 7 is a top view of the antenna shown in FIG. 1; and,

FIG. 8 is a bottom view of the antenna shown in FIG. 1.

1 Claim, 4 Drawing Sheets

Related U.S. Application Data

now Pat. No. 7,609,222, which is a continuation-in-part of application No. 29/304,423, filed on Feb. 29, 2008, now Pat. No. Des. 598,433, said application No. 12/606,636 is a continuation-in-part of application No. 12/040,464, filed on Feb. 29, 2008, now Pat. No. 7,839,347, said application No. 12/606,636 is a continuation-in-part of application No. 29/305,294, filed on Mar. 17, 2008, now Pat. No. Des. 604,276, which is a continuation-in-part of application No. 12/040,464, filed on Feb. 29, 2008, now Pat. No. 7,839,347, and a continuation of application No. 12/050,133, filed on Mar. 17, 2008, now Pat. No. 7,609,222, said application No. 12/606,636 is a continuation-in-part of application No. PCT/US2008/061908, filed on Apr. 29, 2008, and a continuation-in-part of application No. 12/040,464, filed on Feb. 29, 2008, now Pat. No. 7,839,347, and a continuation-in-part of application No. 12/050,133, filed on Mar. 17, 2008, now Pat. No. 7,609,222.
